UNITED STATES PATENT OFFICE.

HARTVIG SORLEY, OF MACOMB, ILLINOIS.

PROPELLING MECHANISM FOR AEROPLANES.

1,269,872.

Specification of Letter's Patent. Patented June 18, 1918.

Original application filed July 15, 1916, Serial No. 109,531. Divided and this application filed May 23, 1917. Serial No. 170,484.

To all whom it may concern:

Be it known that I, HARTVIG SORLEY, a subject of the King of Norway, residing at Macomb, in the county of McDonough and State of Illinois, have invented certain new and useful Improvements in Propelling Mechanism for Aeroplanes, of which the following is a specification.

This invention relates to aeroplanes, and particularly to propelling mechanisms therefor.

The invention has for its primary object to provide an improved propelling mechanism for use in driving aeroplanes of that type illustrated in my copending application, filed July 15, 1916, Serial Number 109,531, of which this application is a division, and which embodies means whereby the momentum of the machine will be utilized to propel the same.

A further object of the invention is to provide improved gearing connections between the motor and the propeller blades, as well as novel means for making and severing the driving connections.

With these objects in view, together with others which will appear as the description proceeds, the invention resides in the novel formation, combination, and arrangement of parts, all as will be described more fully hereinafter, illustrated in the drawings, and particularly pointed out in the claims.

In the drawings:—

Figure 1 is a diagrammatic top plan view of the aeroplane propelling mechanism;

Fig. 2 is a side elevation of an aeroplane equipped with the propelling mechanism;

Fig. 3 is a sectional view taken on line 3—3 of Fig. 1;

Fig. 4 is a similar view taken on line 4—4 of Fig. 1;

Fig. 5 is a sectional elevation taken on line 5—5 of Fig. 1, and showing the gearing from the main to the secondary shafts;

Fig. 6 is a sectional view taken through the ratchet gear; and

Fig. 7 is a sectional view taken on line 7—7 of Fig. 6.

Referring now to the drawings, 11 indicates the aeroplane frame, which supports the floor, and which carries the motor or engine 12 for driving the propellers.

The propelling mechanism includes, in the present instance, four propellers, two of which are located at the sides of the aeroplane and adjacent the forward end thereof, and the other pair of propellers are located one upon each side of the machine and upon the rear end thereof. The forward propellers are indicated at 13, and are of the helicoidal type, and each has affixed to its rear end a rim gear 14. These propellers may be mounted in any suitable manner upon the frame of the aeroplane, and have their axes disposed longitudinally of the said frame.

The aft propellers are indicated at 15 and are of the screw blade type, each being supported upon a forwardly projecting propeller shaft 16 mounted in suitable bearings upon the machine frame. The forward end of each of the shafts 16 carries a pinion 17 which, at certain times, is adapted to receive power through a suitable gear train driven by the helicoidal propellers at the forward end of the machine.

Extending rearwardly from the helicoidal propellers and parallel with the propeller shafts are jack shafts 18, each of which carries at its forward end a pinion 19 in mesh with the teeth of the rim gear 14 on the adjacent helicoidal propeller. Each pinion 19 is rotatably mounted upon its supporting shaft 18, being held thereon against longitudinal movement by the collars 20 and 21 secured to the shaft by pins 22, as illustrated in Fig. 6. Each gear is provided with a ratchet portion 23, the latter being adapted to be engaged by a pawl 24 pivoted upon one of the collars, and a spring 25 yieldably holds the pawl engaged with the teeth of the ratchet portion. From this construction, it is apparent that a driving connection may be established between the rim gear 14 and the shaft 18 only when the former is rotated in one direction, and when the helicoidal propellers rotate at a greater speed than that of the shaft 18, the pawl and ratchet arrangement at once establishes a driving connection between the rim gear and the shaft 18, so that the latter is driven by the helicoidal propeller. The helicoidal propellers are adapted when rotating to transmit power to the aft propellers, so that

should the aeroplane motor fail while the machine is in flight, the power developed in the helicoidal propellers will be sufficient to drive the machine forwardly.

5 The rear end of each jack shaft 18 is equipped with a gear 26, which meshes with a pinion portion 27 affixed to an intermediate gear 28 rotatably mounted upon the aeroplane frame. This gear 28 is in mesh with the 10 pinion 17 upon the forward end of the aft propeller shaft. It is thus seen that the friction of air against the vanes of the helicoidal propeller when the machine is moving forwardly, will develop driving power, 15 through the rim and pinion 14-19, in the shaft 18. The gear train above described transmits this rotary movement in the shaft 18 to the aft propeller shaft, whereupon the driving propellers at the rear of the 20 machine are operated. It is preferred that the helicoidal propellers be relatively large, so as to increase the air resisting surface of the same for the purpose of developing a relatively great amount of power, and the 25 particular helicoidal propeller arrangement also reduces the head-on resistance of the machine when in flight.

Each of the rearwardly projecting blade propeller shafts is equipped with a beveled 30 gear 30, in mesh with a similar gear 31 affixed to the outer end of a transverse driving shaft 32, the latter deriving its rotary movement from the motor or engine 12. The driving shaft of the motor is indicated 35 at 33, and is equipped at its rear end with a beveled gear 34 in mesh with the oppositely disposed gears 35 on the adjacent ends of the transverse driving shafts 32. A clutch mechanism, indicated generally at 36, is arranged in the driving shaft of the motor, so 40 that a power connection between the beveled gear 34 and the engine shaft may be made or severed when desired. A clutch operating rod 37 extends forwardly from the 45 clutch and is connected to the lower end of a lever 38 pivoted adjacent the forward end of the machine and in convenient reach of the driver or aviator.

From the foregoing, it is apparent that 50 when the motor is started, and the driving clutch thrown in, the power developed in the motor will be transmitted through the shafts 32 to the propeller shafts 16, and the propellers on the said shafts will force the 55 machine forwardly. At the same time the propeller shafts are rotated, the jack shafts 18 are also in rotation, as the propeller and jack shafts are connected by the gear train above described. This rotation of the jack 60 shafts, however, will not operate upon the helicoidal propellers, as the ratchet gear at the forward end of the jack shafts will be rotating in such direction that the spring pressed pawls attached to the collars affixed

to the shaft will be idling over the teeth 65 thereof. The friction of air against the helicoidal propellers when the machine is advancing will cause the said propellers to rotate, whereupon the head on resistance offered by air to the advancing machine is 70 reduced, and power is developed in the rim gear 14. Should the engine fail when the machine is in flight, the rapidly rotating helicoidal propellers will drive the jack shafts 18, whereupon the propeller shafts at 75 the rear end of the machine will be rotated. It is thus seen that the forward momentum of the machine is utilized as the source of power by which the propellers may be driven.

While the present disclosure is believed to 80 be the preferred embodiment of the invention, it is to be understood that the invention is not limited thereto, but that various changes in the minor details of construction, arrangement and proportion of parts may be 85 resorted to, if desired, without departing from the spirit of the invention, as defined in the appended claims.

What is claimed is:—

1. In an aeroplane, a motor, a plurality of 90 propellers of both helicoidal and bladed screw type capable of rotating independently of each other, and means for establishing a driving connection between said helicoidal and screw propellers independent of 95 said motor.

2. In an aeroplane, a motor, a plurality of propellers on each side of the longitudinal axis of the aeroplane, the propellers of each side including at least one of helical form, 100 and means for establishing a driving connection between said helicoidal and screw propellers when the former rotates in one direction only.

3. In an aeroplane, a motor, a driving 105 propeller, a connection between said motor and said driving propeller, a helicoidal propeller, and means for establishing a driving connection between said helicoidal and screw propellers when the speed of the former in 110 one direction exceeds that delivered to said driving propeller by said motor.

4. In an aeroplane, a motor, a plurality of propellers of the screw bladed type, a plurality of propellers of helicoidal type, and 115 means for establishing a driving connection between said helicoidal and screw propellers when the former rotates in one direction.

5. In an aeroplane, a motor, laterally extending shafts connected with said motor 120 and driven therefrom, longitudinally extending shafts in driven connection with said laterally extending shafts and carrying propellers, longitudinally extending jack shafts, gear connections between said jack shafts and said longitudinally extending shafts, helicoidal propellers each having a peripheral gear, and a gear and ratchet con-

nection between said peripheral gears and said longitudinal jack shafts.

6. In an aeroplane, a motor, a propeller shaft, a jack shaft, a train of gears establishing a driving connection between said shafts, a driving connection between said motor and propeller shaft, a helicoidal propeller, a gear carried by said propeller, a ratchet connection between said gear and

said jack shaft, and means for breaking the 10 driving connection between said propeller and jacks.

In testimony whereof I affix my signature in presence of two witnesses.

HARTVIG SORLEY.
